DISPLAY CABINET

Richard C. Adams, East Cleveland, and Herbert H. Woodworth, South Euclid, Ohio, assignors to The Sherwin-Williams Company, Cleveland, Ohio, a corporation of Ohio

Application May 8, 1941, Serial No. 392,485

13 Claims. (Cl. 35—55)

This invention relates to display apparatus of the type used for displaying various wall coatings or coverings in a manner such that the colors and decorative values of such coatings or coverings can be conveniently observed and compared and, more particularly, relates to apparatus of this kind in which such coatings or coverings are carried by movable strips of sheet material housed in a cabinet or the like and arranged to extend across or traverse one or more display areas therein.

An object of our invention is to provide improved display apparatus of this character in which novel driving means is employed for shifting the movable strip or strips to display the different wall finishes or coverings carried thereby.

Another object of our invention is to provide improved display apparatus of this character having a pair of winding rollers for each strip and in which the driving means for the rollers includes a shiftable shaft section or clutch means by which the rollers can be selectively driven for moving the strip in one direction or the other.

Yet another object of our invention is to provide an improved display cabinet having therein a plurality of such strips and a plurality of pairs of winding rollers and in which a single driving motor is connected with all of the winding rollers and a manually operable clutch means is provided for each pair of rollers whereby the strip to be driven and its direction of travel can be selectively determined.

A further object of our invention is to provide improved display apparatus of this character having a control switch for the driving motor and in which such switch is arranged to be actuated in response to movement of any one of the manually actuatable clutch operating members.

Other objects and advantages of our invention will be apparent from the following description when taken in conjunction with the accompanying sheets of drawings in which:

Fig. 1 is a front perspective view showing a display cabinet embodying our invention;

Fig. 2 is a side elevation of the cabinet showing certain of the strips and the actuating mechanism therefor;

Fig. 3 is a rear elevation of the cabinet showing the same with portions broken away;

Fig. 4 is a transverse sectional view taken through the cabinet as indicated by line 4—4 of Fig. 2;

Fig. 5 is a partial vertical sectional view taken substantially as indicated by line 5—5 of Fig. 3

and illustrating the arrangement and driving means for one of the strips;

Fig. 6 is a partial sectional plan view taken on line 6—6 of Fig. 5;

5 Fig. 7 is a partial vertical sectional view taken on line 7—7 of Fig. 5;

Fig. 8 is another partial vertical sectional view taken as indicated by line 8—8 of Fig. 2 and showing a portion of the control mechanism;

10 Fig. 9 is a partial vertical sectional view taken on line 9—9 of Fig. 8;

Fig. 10 is a partial vertical sectional view taken adjacent the inner corner of the display recess of the cabinet as indicated by line 10—10 of Fig. 4;

Fig. 11 is a transverse sectional view taken through an edge of the display recess as indicated by line 11—11 of Fig. 4 and showing the construction of the lamp housing; and

15 Fig. 12 is a longitudinal sectional view taken through one of the clutches of the roller driving mechanism.

Further references will now be made to the drawings for the purpose of describing the construction and operation of our display cabinet 20 more in detail, but before proceeding with such detailed description we desire it understood that our invention is not to be regarded as limited to this particular embodiment inasmuch as the invention can be embodied in various specific forms of similar apparatus.

As will be seen from the drawings our display apparatus comprises, in general, an upright cabinet 15 having therein a display recess 16 presenting a plurality of walls or display areas, such cabinet also containing a plurality of strips of sheet material carrying the different wall finishes or coverings to be displayed and power operated mechanism for selectively driving the strips.

25 The cabinet 15 may be of any suitable construction and as here shown comprises an inner frame 15a formed of structural members and a plurality of outer walls or panels 15b formed of sheet metal or other suitable material and attached to such inner frame. The cabinet is so constructed that the recess 16 extends laterally thereinto as shown in Figs. 1 and 4 and opens through two of the adjacent upright outer walls of the cabinet. The recess is defined by, or extends between, two intersecting upright walls or display areas 16a and 16b and two vertically spaced substantially horizontal walls or display areas 16c and 16d. When the cabinet 15 is viewed from the front, as illustrated in Fig. 1, the display recess 16 has the appearance of a corner

30 35 40 45 50 55

portion of a room of which the areas 16a and 16b correspond with the side walls and the areas 16c and 16d correspond respectively with the floor and ceiling. The cabinet is constructed with suitable walls or panels therein corresponding with these display areas, and, as will be presently explained more in detail, strips of sheet material carrying the different wall finishes or coverings are arranged to extend across and in front of such walls or panels. In Fig. 4 we show two such upright walls or panels 17a and 17b in the cabinet corresponding with the upright display areas 16a and 16b of the recess 16. We also show in Fig. 4 the strips 18 and 19 of sheet material extending across and in front of the upright walls 17a and 17b. In Figs. 4 and 5 we show vertically spaced panels or walls 20 and 21 built into the cabinet to correspond with the display areas 16c and 16d and forming the floor and ceiling of the display recess. In Fig. 5 we show a strip 22, similar to the strips 18 and 19, extending across and in front of the ceiling panel 21 and in Fig. 4 we have represented a portion of a rug or other covering 23 which may be laid on the floor 20.

The strips 18, 19, and 22 may be formed of paper, fabric, or other flexible material and may each have a plurality of contiguous or adjacent sections thereon representing the different wall coverings or finishes to be displayed. These sections correspond substantially in size and shape with the panels 17a, 17b and 21, across which the strips extend, so that by moving these strips across the panels the wall coverings or finishes to be viewed in the display areas 16a, 16b, and 16d of the recess 16 can be changed as desired.

The strips are carried by pairs of winding rollers which are rotatably supported in the cabinet and are adapted to be selectively driven to move the strips in either direction across the display areas and thereby bring the different sections substantially into register with such display areas. The strip 18 which serves the display area 16b is carried by the upper and lower winding rollers 24a and 24b and has its opposite ends connected to these rollers. For directing the strips across the face of the upright panel 17a we may also provide a pair of upper and lower guide rollers 25a and 25b as shown in Fig. 2. Similarly the strip 19 which serves the display area 16a is carried by a pair of upper and lower winding rollers 26a and 26b and is directed across the face of the upright panel 17b by a pair of upper and lower guide rollers 27a and 27b. The ceiling strip 22 has its ends connected to a pair of winding rollers 28a and 28b as shown in Figs. 5 and 6 and is directed across the face of the ceiling panel 21 by the guide rollers 29a and 29b.

The driving means for the winding rollers will next be described in detail. For the winding rollers 24a and 24b of the strip 18 we provide a pair of upright substantially aligned shafts 30 and 31 which, as shown in Fig. 2, are connected respectively with the upper and lower winding rollers by pairs of bevel gears 30a and 31a. The upright shafts 30 and 31 may be rotatably supported in suitable bearings 32 mounted on the inner frame 15a of the cabinet. Between the aligned upright shafts 30 and 31 we provide a shaft section 33 which is adapted to be positively driven and to be connected with one or the other of the upright shafts depending upon which of the winding rollers is to be driven. The adjacent ends of the shafts 30 and 33 carry cooperating clutch members 35 and 36 of a clutch 37 and

the adjacent ends of the shafts 31 and 33 carry similar clutch members 38 and 39 of a clutch 40. The positively driven shaft section 33 is rotatably supported by one or more bearings 41 and is axially slidable therein for engaging one or the other of the clutches 37 and 40. The driving means for the shaft section 33 may comprise a worm gear 42 carried thereby and a worm 43 meshing with such gear and driven from an electric motor 44 by means of a belt 45 extending around pulleys 46 and 47 carried respectively by the worm shaft 43a and the motor shaft 44a.

The driven shaft section 33 may be shifted by any suitable control means and in this instance, we show a manually operable lever 48 for this purpose. The lever 48 has its inner end pivotally connected or fulcrumed on the frame 15a as indicated at 49 and its outer end extends through a slot in the front outer wall of the cabinet and carries an operating handle or knob 50. Adjacent its inner or fulcrumed end the lever 48 has a forked portion 48a connected with the shaft 33 through sleeve 51 arranged thereon so that swinging of the lever upwardly on its fulcrum will lift the shaft to engage the clutch 37, and downward swinging of the lever will lower the shaft to engage the clutch 40. Thus when the control knob 50 is lifted, the clutch 37 will be engaged and the upper winding roller 24a will be driven by the shaft 30 and the strip 18 will move upwardly across the display area 16b; and downward movement of the control knob 50 will cause the lower winding roller 24b to be driven through the clutch 40 and the shaft 31 to cause corresponding downward movement of the strip across the display area 16b. When the winding roller 24a is being driven the strip is withdrawn from the lower winding roller 24b and such withdrawal of the strip will cause the shaft 31 and the bevel gear 31a to be driven as idlers. At this time the shaft 31 will rotate in a direction opposite to that of the driven shaft section 33 but there will be no interference between these shafts inasmuch as the clutch members 38 and 39 of the clutch 40 are separated or disengaged.

For driving the winding rollers 26a and 26b we provide another such pair of upright substantially aligned shafts 53 and 54 and a positively driven intermediate shaft section 55. The shafts 53, 54, and 55 may be arranged adjacent the upright shafts 30, 31, and 33 and the intermediate shaft section 55 may be driven from the shaft section 33 through gears 56 and 57. The upper end of the shaft 53 may be connected with the upper winding roller 26a by a pair of bevel gears 58 and the lower end of the shaft 54 may be connected with the lower winding roller 26b by a pair of bevel gears 59. The adjacent ends of the shafts 53 and 55 carry cooperating members 60 and 61 of a clutch 62 and the adjacent ends of the shafts 54 and 55 carry cooperating members 63 and 64 of a clutch 65.

The driven shaft section 55 is rotatable in suitable bearings 66 and is axially slidable therein for engaging one or the other of the clutches 62 and 65. We provide a control lever 67 which is fulcrumed on the frame 15a in a manner similar to the control lever 48 and has a forked portion 67a connected with the shaft 55 through a sleeve 68 whereby this shaft can be lifted to engage the clutch 62 or lowered to engage the clutch 65. The outer end of the lever 67 projects through a slot of the outer wall of the cabinet and carries an operating knob 69. When the knob 69 is lifted the clutch 62 will be engaged to drive the upper

winding roller 26a and cause upward movement of the strip 19 across the panel 17b and downward movement of the control knob will engage the clutch 65 and cause the lower winding roller 26b to be driven thereby moving the strip 19 downwardly across this panel.

The clutches 37, 40, 62, and 65 may be of any suitable construction such as that represented in Fig. 12. As here shown these clutches may be of the friction type and may have a disk 70 of suitable friction material disposed between the cooperating members thereof. This friction disk serves to drivingly connect the clutch members with each other whenever they are pressed against the disk by relative axial shifting. The friction disk may be retained in place between the clutch members by extending one of the aligned shafts therethrough.

The winding rollers 28a and 28b for the ceiling strip 22 can be driven by an arrangement of shafts similar to that above described for the winding rollers of the strips 18 and 19 or, as shown in this instance, may be connected with a pair of relatively short spaced parallel shafts 71 and 72 by the chains 73 and 74 extending over sprockets 71a and 72a carried by these shafts. A positively driven shaft 75 is arranged to extend between a pair of worm gears 76 and 77 mounted on the shafts 71 and 72 and carries a worm 78 which is disengaged from the worm gears when the shaft 75 is in an intermediate or neutral position. This shaft is arranged for swinging movement to bring the worm 78 in mesh with one or the other of the worm gears 76 and 77 depending upon which of the winding rollers is to be driven. The shaft 75 may have a pulley 79 thereon which is connected with the pulley 46 of the motor 44 by a belt 80.

To provide for such swinging of the shaft 75 we may arrange this shaft with one end thereof journaled in a rocking bearing 81 and its other end journaled in a bearing 82 carried by a swinging operating lever 83. The inner end of the lever 83 is pivoted on a fulcrum pin 84 so that this lever swings about the same axis as that about which the bearing 81 rocks. The outer end of the lever 83 may be connected with a link 85 which is, in turn, connected with an operating lever 86 arranged adjacent the operating levers 61 and 48. The inner end of the lever 86 may be fulcrumed on the frame 15a as indicated at 87 and its outer end may extend through a slot into the outer front wall of the cabinet and may carry an operating knob 88. When the knob 88 is lifted, upward motion will be transmitted through the link 85 to lift the lever 83 and the outer end of the shaft 75, thereby bringing the worm 78 into mesh with the worm gear 76. This will result in the winding roller 28a being driven in a direction to take up the strip 22 and cause the same to move across the ceiling panel 21 toward the left as seen in Fig. 5. Downward movement of the control knob 88 will, in a similar manner, cause the worm 78 to mesh with the worm gear 77 and drive the winding roller 28b in a direction to cause the strip 22 to move across the ceiling panel 21 in the opposite direction, that is, towards the right as seen in Fig. 5.

The driving motor 44 may be operated continuously while our display cabinet is in use, but we prefer to provide control means for the motor such that it will be started only when one of the control knobs is moved to cause a desired actuation of one of the strips. We also prefer to have the motor automatically deenergized as soon as

the control knob is moved back to its neutral position for stopping the movement of the strip. In Figs. 8 and 9 we show apparatus for controlling the energization of the motor in response to movement of any one of the control knobs 50, 69, and 88. This control apparatus comprises a switch 90 located in the motor circuit and switch actuating means for closing the switch in response to either upward or downward movement of one of the control knobs from its neutral position and for opening the switch when the knob is returned to its neutral position.

The switch 90 may be of the tilting mercury-globe type and may be mounted on an arm 91 carried by a rock shaft 92 which extends transversely to the control levers 48, 61, and 86. Each of the control levers extends between a pair of stationary cams 93 and carries a block 94 which is guided between the spaced cams and is slidable on the lever. The block 94 carries a pair of cam followers in the form of the rollers 95. The cams 93 are so formed or shaped as to provide a low or neutral point 96, which is located opposite the neutral position of the control lever, and a pair of oppositely inclined cam portions 97 extending away from such neutral point. When the control lever is moved either upwardly or downwardly away from its neutral or mid position, the followers 95 ride up on the inclined portions 97 and cause the block 94 to be slid inwardly on the lever against the action of a compression spring 98.

The inward movement of the block 94 is made to oscillate the rock shaft 92 as by providing the latter with a depending arm 99 arranged to be engaged by the pivot pin 100 of one of the cam followers 95. The depending arms 99 correspond in number with the control levers and extend adjacent thereto as shown in Fig. 8. Each of the depending levers 99 may have opposite inclined portions 99a thereon against one or the other of which the pin 100 will bear and cause oscillation of the rock shaft 92 in response to swinging of the control lever. The arm 91 of the rock shaft 92 and the switch 90 carried by this arm are so arranged that when the control knobs are all in the neutral position, that is to say, when the cam followers 95 are at the low points 96 of the cams, the switch will be in its open position and the motor 44 will be deenergized. The springs 98 normally urge the blocks 94 outwardly so that the cam followers 95 will react on the cam faces 97 to hold the control levers in the intermediate or neutral position in which the switch 90 is open and the motor is deenergized. A torsional spring 101 may be arranged on the rock shaft 92 so as to act in a direction tending to hold the arms 99 against the pins 100 and to normally rock the shaft in a direction to urge the switch 90 toward its open position. With the control apparatus just described it will be seen that as soon as any one of the control knobs 50, 69, or 88 is moved either upwardly or downwardly from its neutral position the switch 90 will be tilted up to energize the motor 44 and one of the clutches, of the pair corresponding with the control knob which is moved, will be engaged to drive the corresponding winding roller.

For illuminating the display areas of the recess 16 we may provide incandescent lamps 102 at one or more points adjacent the lower outer edges of the recess. Housings 103 for the incandescent lamps 102 may be formed by curving portions of the outer walls of the cabinet 15 inwardly part way into the recess 16 as shown in

Figs. 1 and 11. A reflector 104 may form a part of the lamp housing and may be mounted in back of the incandescent lamps 102 and in a position to reflect light into the recess 16. The lamp housing 103 may also include a transparent or colored wall section 105 extending between the one edge of the reflector 104 and the frame structure 15a as shown in Fig. 11. The lamps 102 can be turned on and off by means of a suitable switch 102a on the front of the cabinet. As shown in Fig. 1, the lamps 102 may be located in one or all of the bottom, side and top outer edges of the display recess.

As a retaining means for the adjacent edges of the upright strips 18 and 19 we may provide an upright tube or rod 106 formed of transparent material or any other suitable substance. This tube may be mounted in the inner corner of the recess 16 so as to overlie the edges of the strips 18 and 19 as a guide and retain such edges smoothly in place. The tube 106 may be mounted in the cabinet by a pair of upper and lower projections 107 and 108 arranged to extend into the ends of the tube. One of the projections, in this instance the lower projection 108, is carried by a resilient arm 109 which can be flexed in a direction to withdraw the projection from the end of the tube to permit the latter to be removed from the cabinet when this is desirable. If desired, strips 110 of suitable material may be located along the inner edges of the recess adjacent the floor or ceiling, or both, to represent a mopboard or molding.

From the foregoing description and the accompanying drawings it will now be readily understood that we have provided an improved display cabinet embodying novel actuating means for strips carrying different wall finishes or coverings to be displayed. Moreover, it will be seen that we have provided a power means for driving the strips and a simple and sensitive control arrangement by which the movement of the strips can be conveniently and accurately controlled.

While we have illustrated and described our improved display cabinet in a more or less detailed manner, it will be understood, of course, that we do not wish to be limited to the precise details and arrangements herein disclosed but regard our invention as including such changes and modifications as do not constitute a departure from the spirit of the invention and the scope of the appended claims.

Having thus described our invention, we claim:

1. A display device of the character described comprising a cabinet having a recess extending laterally thereinto and having sides defined by two intersecting upright walls, a pair of winding rollers associated with each of said walls, a strip of sheet material extending in front of each wall and having its ends connected with the winding rollers associated with such wall, each such strip having sections representing different wall finishes or coverings, a pair of substantially aligned shafts associated with each pair of winding rollers with one shaft of the pair connected with each roller, a positively driven shaft disposed between each such pair of aligned shafts, each positively driven shaft being axially shiftable for reversing the direction of travel of the corresponding strip and having means for establishing in response to such axial shifting a driving connection with one of the paired shafts aligned therewith, and means for causing such shifting of said shiftable shafts.

2. A display device of the character described

comprising a cabinet having a recess extending laterally thereinto and defined by a pair of intersecting upright walls and a pair of vertically spaced substantially horizontal walls, pairs of winding rollers in said cabinet, strips of sheet material having sections representing different wall finishes or coverings and extending in front of said upright walls and at least one of said horizontal walls, said strips having their ends connected with the respective pairs of winding rollers, rotatable shafts connected with the respective winding rollers and arranged in pairs corresponding with the paired rollers, a positively driven shaft associated with each of said pairs of shafts, each positively driven shaft being shiftable for reversing the direction of travel of the corresponding strip and having means for establishing in response to such shifting a driving connection with one of the shafts paired therewith, and means for causing such shifting of said shiftable shafts.

3. In display apparatus, a cabinet having a recess extending laterally thereinto and a wall therein defining a side of said recess, a pair of winding rollers adjacent two opposed edges of said wall, a strip of sheet material extending across said wall and having its ends connected to said winding rollers, said strip having sections of substantially the same shape and area as said wall and representing different wall finishes or coverings, a pair of rotatable shafts connected with the respective winding rollers, a third rotatable shaft extending between the shafts of said pair, means for rotatably driving said third shaft, cooperating clutch elements on said pair of shafts and said third shaft, said third shaft being shiftable to engage the clutch element thereof with the clutch element of one or the other of the paired shafts, and means for shifting said third shaft.

4. In display apparatus, a cabinet having a recess extending laterally thereinto and a wall therein defining a side of said recess, a pair of winding rollers adjacent two opposed edges of said wall, a strip of sheet material extending across said wall and having its ends connected to said winding rollers, said strip having sections of substantially the same shape and area as said wall and representing different wall finishes or coverings, a pair of substantially axially aligned rotatable shafts having their adjacent ends spaced apart and their remote ends connected to said winding rollers, clutch elements carried by said adjacent shaft ends, a third shaft disposed between and in substantial axial alignment with said pair of shafts and having clutch elements at opposite ends thereof adapted to operate with the clutch elements of said pair of shafts, means mounting said third shaft for axial shifting, means for axially shifting said third shaft to engage one pair or the other of said clutch elements, and means for driving said third shaft.

5. In a display apparatus of the character described, a support having display areas thereon, a plurality of pairs of winding rollers on said support, strips of sheet material arranged to traverse said display areas and having their ends connected to the respective pairs of rollers, shafting for driving each pair of rollers including a shaft section adapted to be selectively shifted to determine the direction of travel of the strip, a shifting member for each shiftable shaft section, a common driving motor for driving the shafting for all of the pairs of winding rollers,

and a switch controlling said motor and arranged to be actuated in response to movement of any one of such shifting members.

6. In display apparatus of the character described, a support having a display area thereon, a pair of winding rollers on the support, a strip of sheet material arranged to traverse said display area and having its ends connected with said rollers, shafting for driving said rollers including a driven shaft section which is selectively shiftable from a neutral position to determine the direction of travel of the strip, a driving motor connected with said driven shaft section, a lever connected with said driven shaft section and being movable from a neutral position for causing such shifting of the driven shaft section, and a switch controlling said motor and arranged to be actuated by movement of said lever, said switch having an off position corresponding with the neutral position of said lever.

7. In display apparatus of the character described, a support having a display area thereon, a pair of winding rollers on the support, a strip of sheet material arranged to traverse said display area and having its ends connected with said rollers, means for selectively driving said rollers including a motor and a shiftable clutch means, a control member movable from a neutral position for shifting said clutch means, means biasing said control member toward its neutral position, and a switch for said motor arranged to be actuated by movement of said control member and having an off position corresponding with the neutral position of the control member.

8. In display apparatus of the character described, a support having a plurality of pairs of winding rollers thereon, a driving motor, means connecting said motor with said winding rollers, means for selectively controlling the operation of said rollers including a control lever associated with each pair of rollers and movable to either side of a neutral position, a switch for controlling the energization of said motor, and means connected with said switch to cause actuation thereof in response to movement of any one of such control levers to either side of its neutral position.

9. In display apparatus of the character described, a support having a plurality of pairs of winding rollers thereon, a driving motor, means connecting said motor with said winding rollers, means for selectively controlling the operation of said rollers including a control lever associated with each pair of rollers and movable to either side of a neutral position, a switch for controlling the energization of said motor, a switch-actuating shaft extending adjacent said control levers, and cam means associated with the respective control levers and arranged to impart switch-actuating movement to said shaft in response to movement of any one of such control levers to either side of its neutral position.

10. In display apparatus of the character described, a support having a pair of winding rollers thereon, a driving motor, means connecting said motor with said winding rollers, means for selectively controlling the operation of said rollers

including a control lever movable to either side of a neutral position, a cam having a neutral point located to correspond with the neutral position of said lever and also having oppositely sloping portions on opposite sides of said neutral point, a switch controlling the energization of said motor, and means for actuating the switch including a follower engaging the cam and adapted to be actuated thereby in response to movement of said control lever to either side of its neutral position.

11. In display apparatus of the character described, a support having a pair of winding rollers thereon, a driving motor, means connecting said motor with said winding rollers, means for selectively controlling the operation of said rollers including a control lever movable to either side of a neutral position, a stationary cam having a low point located to correspond with the neutral position of said lever and also having oppositely sloping portions on opposite sides of said low point, a switch controlling the energization of said motor, a follower shiftable on said control lever and engaging said cam, a spring urging said follower toward the low point of said cam, and pivoted means arranged to be rocked by said follower for actuating said switch in response to movement of said lever to either side of its neutral position.

12. In display apparatus of the character described, a support having a pair of winding rollers thereon, a driving motor, means connecting said motor with said winding rollers, means for selectively controlling the operation of said rollers including a control lever movable to either side of a neutral position, a stationary cam having a low point located to correspond with the neutral position of said lever and also having oppositely sloping portions on opposite sides of said low point, a follower shiftable on said control lever and engaging said cam, a spring on said lever urging said follower toward the low point of said cam, pivoted means arranged to be rocked by said follower in response to movement of said lever to either side of its neutral position, and a switch of the tilting mercury-globule type carried by said pivoted means and controlling the energization of said motor.

13. In display apparatus of the character described, a support having a display area thereon, a pair of winding rollers on the support, a strip of sheet material arranged to traverse said display area and having its ends connected with said rollers, a pair of spaced shafts connected with the respective winding rollers, worm gears on said shafts, a third shaft having a worm thereon and normally occupying a neutral position with the worm disengaged from said gears, means mounting said third shaft for swinging in either direction from said neutral position to engage said worm with one or the other of said worm gears, means for driving said third shaft, and means for swinging said third shaft.
